UNITED STATES PATENT OFFICE.

JOHN B. PARKER, OF WASHINGTON, DISTRICT OF COLUMBIA.

WASHING APPARATUS FOR LABORATORIES.

Application filed April 13, 1926. Serial No. 101,785.

The present invention relates to washing and testing apparatus for laboratories, and consists in the combinations and arrangements of elements hereinafter described and particularly set forth in the accompanying claims, and its main use is in preparation of materials for histological study.

One object of the invention resides in the use of a number of tubes mounted and freely suspended in a receptacle or basin in such a manner that materials may easily be washed by liquids (usually water) passing downwards through the tubes and freely out at their lower ends, and in this manner shortening the time of the washing process.

Another object of the invention is to arrange the tubes in series under a pipe in such a manner that one or more may be used at a time and that the flow of liquid can be regulated to only a few drops per minute when so desired. This is accomplished by the use of specially constructed plugs in the feed valves so that by setting the plugs in different angular positions a greater or smaller amount of washing liquid will be fed to the tubes.

This apparatus will thus enable the histologist, in the preparation of materials, to wash out from them quickly and with the least trouble to himself, the chemical or reagent used in the killing or fixing process.

Furthermore, I arrange the tubes in the apparatus so that they may be removed individually therefrom or together with the receptacle or basin. For this purpose a clip for each tube is provided to grip the top thereof and a foot or leg beneath it to raise it from the bottom of the basin, thereby permitting free flow of washing liquid from the bottom end of the tube in all radial directions.

The basin has a locking device for securely fastening it to the stand of the apparatus, in order to prevent accidents and insure the proper registration between the valve spouts and the tubes. This locking device is made to quickly disengage the basin from the stand when the latter is to be removed.

At the top of the apparatus is fixedly mounted a feed pipe for water or other liquid used in washing the material and on

this pipe a plurality of valves is provided, one for each tube.

In the accompanying drawings one embodiment of the invention has been illustrated, and

Figure 1 represents a front elevation, partly in section, of the apparatus;

Figure 2 a horizontal sectional view along the line 2—2 of Figure 1;

Figure 3 a vertical section along line 3—3 of Figure 1;

Figure 4 a vertical section in larger scale of one of the details;

Figure 5 a section along line 5—5 of Figure 4;

Figure 6 a fragmentary side view of the lower end of a tube; and

Figure 7 a bottom plan view of Figure 6.

In the drawings, reference numeral 10 denotes a rack or stand, preferably of metal, and comprising end posts 11 extending upwardly from the bottom 9 on feet 12. Between the posts is fixed a pipe 13 closed at one end and open at the other, as at 14, to receive a hose or other connection with a source of supply of the water or other liquid used for the washing.

On the under side of the pipe 13 is to be found a series of outlet orifices 14 with valves 15 having a narrow tapering spout 16, as best seen in Figures 4 and 5. The valve plug 17 is in the usual manner provided with a transverse passage 18 adapted to connect the orifice 14 with the spout 16 when the valve is fully open. Small grooves 19, 19' run in opposite directions from the passage 18 circumferentially on the surface of the plug and diminish in sectional area, 19' being preferably smaller than 19. In this manner the valve may not only be set fully closed or fully open, but also, when the plug is partly turned, to permit a very slow dripping from the spout when so desired. The usual stops to limit the turning of the plug are provided in the valve.

On the bottom 9 rests a receptacle or basin 20 of the full width and length of the rack or stand 10 and terminating a short distance below the end of the spouts 16 to permit easy removal. In order to properly position the basin in the stand or rack 10, the

basin has a stop 21 at each end adapted to engage one side of the end posts 11. A spring snap 22 is also provided at each end of the basin 20 for engaging the other side 5 of the end posts 11, thus securing the basin in place.

Along the top edge of the basin is arranged a series of clips 23 having the same spacing as the valves 15, and each adapted 10 to grip a tube 24 and hold it upright directly under the corresponding valve spout 16 so that the latter can discharge into the tube. An overflow pipe is shown at 30 in order to maintain a constant level of the 15 washing fluid while the washing process is carried out.

The tube 24 is preferably cylindrical and open at both ends. Its upper end, as already described, is suspended from the clip 23, but the lower end is gripped by a spring clamp 25 which has a leg 26 by means of which the tube is supported on the bottom of the basin 20 at a height therefrom to permit free passage of the liquid from the tube 24 in 25 all directions. In other words, the lower end of the tube is in this manner spaced from the bottom of the basin about half the diameter of the tube in order to make sure that the end of the tube does not touch the 30 bottom of the basin.

The spring clamp 25 also serves another purpose, namely to secure the strainer 27 in position under and around the lower end of the tube in order to retain the material to be 35 washed in the tube. After placing the strainer in this manner on the tube, the clamp is slipped over and around it, giving sufficient pressure to hold it in place. The strainer may be made of any suitable material, such as felt, metal gauze, or any 40 fabric best suited for the purpose of washing the contents of the tubes.

After the material to be washed has been placed in the tubes and the tubes inserted 45 in the clips in the basin, the latter is placed in the rack and one or another of the valves is opened fully or partly to permit the water to enter at the top of the tube and escape at the bottom thereof after having washed the 50 contents of the tube. The water may be kept running continuously and the overflow is taken care of by the pipe 30. Any individual tube may thereupon be removed and reinserted or replaced by another at any time, 55 or the entire basin may be removed at the will of the operator.

The above description discloses one embodiment of my invention, but it is obvious that several modifications may be made 60 within the spirit and scope of my invention.

What I claim as new is:

1. A tube having inlet and outlet openings of substantially the same cross sectional area, a strainer for the outlet opening, and means having a downwardly di- 65

rected leg portion for removably securing the strainer exteriorly on the tube.

2. A tube having inlet and outlet openings of substantially the same cross sectional area, a strainer for the outlet opening, and means including a coiled wire for removably securing the strainer exteriorly on the tube and spacing the outlet end thereof from a supporting element. 70

3. A tube having inlet and outlet openings of substantially the same cross sectional area, a strainer for the outlet opening, and means for removably securing the strainer exteriorly on the tube and spacing the outlet end thereof from a supporting element, 75 said means comprising a coiled wire having a downwardly extending leg portion. 80

4. In an apparatus of the class described, a basin, tubes as described in claim 2, and clips adjacent the top of the basin forming suspension members for said tubes; the bottom of the basin forming the supporting element for the tubes. 85

5. In an apparatus of the class described, a stand, a supply pipe carried by the stand and provided with spaced outlet orifices, a basin removably supported on the stand, tubes as described in claim 2, clips on the basin forming suspension members for said tubes spaced to permit registry between said orifices and said tubes, and discharging members connected with the orifices adapted to feed a required amount of liquid into the tubes from said supply pipe. 90

6. In an apparatus of the class described, a stand, a supply pipe carried by the stand and provided with spaced outlet orifices, a basin removably supported on the stand, locking means between the stand and the basin, tubes as described in claim 2, clips on the basin forming suspension members for said tubes spaced to permit the registering between said orifices and said tubes, and discharging members connected with the orifices adapted to feed a required amount of liquid into the tubes from said supply pipe. 100

7. In an apparatus of the class described, a stand, a supply pipe carried by the stand and provided with spaced outlet orifices, a basin removably supported on the stand, locking members between the stand and the basin, tubes as described in claim 2, suspension members on the basin comprising metal clips for said tubes spaced to permit registry between said orifices and said tubes, and discharging members connected with the orifices adapted to feed a required amount of liquid into the tubes from said supply pipe. 110

8. A tube having inlet and outlet openings of substantially the same sectional area, a strainer attached over the outlet opening, and means comprising a wire clip with a downward projection for spacing the outlet end of the tube from a supporting element. 115

9. The combination with a supporting element of a tube having inlet and outlet openings of substantially the same sectional area, a strainer attached over the outlet opening, and means for spacing the outlet end of the tube from the supporting element, said means comprising a coiled spring adapted to embrace the tube and provided with a leg

portion situated in substantially the axial direction of the tube and resting on said supporting element. 10

In witness whereof, I have hereunto set my hand at Washington, District of Columbia.

JOHN B. PARKER.
